UNITED STATES PATENT OFFICE

149,784

DESIGN FOR A PUZZLE FINGER RING

James D. Anderson, Albuquerque, N. Mex.

Application March 18, 1947, Serial No. 137,700

Term of patent 7 years

(Cl. D45—10)

To all whom it may concern:

Be it known that I, James D. Anderson, a citizen of the United States, residing at Albuquerque, in the county of Bernalillo and State of New Mexico, have invented a new, original, and ornamental Design for a Puzzle Finger Ring, of which the following is a specification, reference being had to the accompanying drawings forming a part hereof.

Figure 1 is a top plan view of a puzzle finger ring showing my new design;

Figure 2 is an edge of the ring; and

Figure 3 is an end elevation thereof.

I claim:

The ornamental design for a puzzle finger ring, as shown.

JAMES D. ANDERSON.
